UNITED STATES PATENT OFFICE

99,708

DESIGN FOR A BUILDING

Guy B. de Vall, New York, N. Y.

Application March 6, 1936, Serial No. 61,503

Term of patent 14 years

To all whom it may concern:

Be it known that I, Guy B. de Vall, a citizen of the Dominion of Canada, residing at Borough of Manhattan, city, county, and State of New York, have invented a new, original, and ornamental Design for a Building, of which the following is a specification, reference being had to the accompanying drawings, forming part thereof.

Fig. 1 is a perspective view showing the front of the design, and

Fig. 2 is a perspective view showing the rear of the design.

The design illustrated is intended to be used as a memorial, shrine, altar, or similar building structure.

I claim:

The ornamental design for a building, as shown and described.

GUY B. DE VALL.
